SPRING CUSHION FOR FURNITURE

Frank X. Nemmer and Albert W. Nemmer,
Cheektowaga, N. Y.

Application February 17, 1934, Serial No. 711,746

2 Claims. (Cl. 155—180)

This invention relates to a spring cushion for use in furniture such as chairs, davenport, lounges, vehicles and the like.

The objects of this invention are to provide an improved base for the cushion which consists essentially of a bottom and side walls formed of sheet metal and thus furnishes a strong and durable support for the structure mounted thereon, and to provide improved means for mounting this base on the furniture frame and securing the fabric covering of the cushion to the side and rear parts of the base.

This application is a division in part of an application Serial No. 630,436 filed August 25, 1932.

In the accompanying drawings:

Figure 1 is a fragmentary top plan view of a davenport embodying these improvements.

Figure 2 is a vertical transverse section, on an enlarged scale, taken on line 2—2 Fig. 1.

Figure 3 is a fragmentary vertical longitudinal section, on an enlarged scale, taken on line 3—3 Fig. 1.

Figure 4 is a fragmentary vertical section, on an enlarged scale, showing the manner of mounting the base of the cushion on the frame and securing the spring covering to the base.

Figure 5 is a fragmentary vertical section of the base detached from the frame and spring covering.

Figure 6 is a vertical section taken on line 6—6 Fig. 5.

Figure 7 is a view similar to Fig. 4, showing a modification of this invention.

In the following description similar characters of reference indicate like parts in the several figures of the drawings:

In its general organization this cushion for furniture comprises a base which is adapted to be mounted on the frame of a chair, davenport, lounge or other piece of furniture, a resilient means mounted on this base, and a covering extending over the resilient means and attached at its margin to the base and a part of the furniture frame.

Although the furniture frame may be variously constructed to suit the particular character of the piece of furniture which is to be manufactured and receive the cushion embodying the present invention, the furniture frame which is shown in the drawings as an example of one suitable for this purpose is of rectangular or oblong form and comprises front and rear longitudinal bars or rails 20, 21 and transverse end

bars or rails 22 connecting the corresponding ends of the front and rear bars.

These furniture bars may be constructed of any suitable material but wood is preferably used for this purpose and each of these bars is provided with a rabbet on its upper inner corner so as to form an upwardly facing shoulder 23 thereon.

The base of the spring cushion is constructed in the form of a rectangular box or pan which opens upwardly and comprises a horizontal bottom 24, upright longitudinal side walls 25, 26 extending upwardly from the front and rear edges of the bottom, and upright transverse end walls 27 extending upwardly from the transverse edges of the bottom and connecting with the corresponding ends of the longitudinal walls 25, 26. The bottom and walls of this base are preferably constructed of sheet metal such as sheet steel which is stamped or formed into suitable shape, but if desired other metals or materials may be employed for this purpose.

This box-shaped base is arranged within the furniture frame so that the bottom extends completely across the space within this frame and the upright walls of the base engage with the inner sides of the bars thereof.

Various means may be employed for supporting this base on the furniture frame together with the parts mounted on the base, but such support is preferably effected by providing the upper edge of each of the upright walls of the base with a flange 28 which extends laterally outward and downward from the upper edge of each base wall so that the same has the form of a hook and produces a downwardly opening channel or groove 29 on the underside of this flange, as shown in Figs. 2, 3, 4 and 7. When mounting this base on the furniture frame the lower edges of the flanges 28 rest on the shoulders 23 of the rabbets 40 on the several frame bars, and the tops of these flanges are flush with the upper sides of the frame bars, as shown in the figures just mentioned.

When the base is of oblong form and of considerable length, as is usually the case when a piece of furniture receiving this spring cushion consists of a davenport, lounge or similar article of furniture, then the bottom of the base is reinforced or strengthened at one or more points intermediate of its length so as to increase its rigidity and durability. In the drawings a single reinforcement or strengthening device is shown for this purpose and this comprises a transverse reinforcing bar or brace 30 constructed of sheet metal so as to be of hollow form, and secured on its

underside to the upper side of the bottom 24, while its opposite ends are secured by means of brackets 17 to the adjacent parts of the inner sides of the front and rear walls of the base, as shown in Figs. 5 1 and 3.

Within the base is arranged the resilient means which provide the yielding support forming part of the cushion, and these yielding means include a plurality of upright helical springs 31. The 10 means for fastening each of these springs to the bottom of the base preferably consist of a plurality of attaching loops 32 which are struck up from the bottom of the base and receive the lowermost convolution of the respective spring, as shown in 15 Figs. 1, 2 and 3.

Above the group of springs and adjacent to the marginal parts of the outermost springs of this group a top retaining frame is provided which 20 preferably consists of wire and comprises front and rear longitudinal rods 33, 34 which are fastened to the outer parts of the uppermost convolutions of the springs at the front and rear end of the cushion, and transverse rods 35 connecting the corresponding ends of the longitudinal rods 33, 34 and fastened to the outermost parts of the uppermost convolutions of the springs arranged at opposite ends of the cushion.

The connection between the rods of the top retaining frame and each of said springs is preferably effected by means of a clip 36. A plurality of longitudinal stay wires 40 are connected with the uppermost convolutions of the several springs and the transverse rods 35 of the top retaining frame, and a plurality of transverse stay wires 41 are connected with the uppermost convolutions of the several springs and the front and rear longitudinal rods 33 and 34 of the top retaining frame.

The numeral 44 represents a plurality of upright stop lines or flexible members which are preferably constructed in the form of chains and are connected at their upper ends at intervals with the several bars or rods of the top retaining frame, while their lower ends are connected with the upper edge of the walls of the base. The last-mentioned connection is preferably effected through the medium of corrugated or crimped wires 45 which are secured lengthwise to the upper side of the flanges 28 on the base walls so as to form a plurality of upwardly projecting loops, to one or the other of which the lower end of an adjacent stop line or chain 44 may be secured.

The numeral 46 represents additional stop lines or chains which are inclined and connected at their upper rear ends with the inner parts of the front springs at the top thereof, while their lower front ends are connected with one or another of the loops of the crimped wire 45 on the front part of the base in the same manner in which this is done with reference to the stop lines or chains 44.

For the purpose of imparting an ornamental appearance to the front of the davenport, lounge or chair the spring cushion is provided on its upper front part with one or more shape bars or rods 51, which, as shown in Fig. 1, are curved forwardly and connected by means of clips 52 or otherwise with the front rod or bar 33 of the top retaining frame.

Inclined anti-swaying bars or rods 53 are provided, each of which is arranged at an angle and pivotally connected at its rear lower end with the bottom of the base by means of a pivot hook 54 at its rear end and engaging with a pivot loop 55 which is struck up from the adjacent part of the

base bottom, as shown in Figs. 1 and 2. At its front end each of the stay rods or anti-swaying bars 53 is provided with an eye 56 which is bent around a downwardly projecting crimp 57 on one of the shape bars 51. The intermediate part of each of the anti-swaying bars is provided with a laterally projecting crimp or loop 58 which interlocks with a crimp or loop 59 on the adjacent part of the front rod or bar 33 of the top frame.

A covering extends over the top of the resilient means of the cushion, which covering preferably consists of any suitable flexible fabric or textile material similar to that now commonly in use for upholstery work. This covering comprises an upper substantially horizontal sheet 60 which rests 10 on the top of the springs, the top retaining frame, the shape bars and the stay wires connected therewith; end flaps 61 extending downwardly from opposite transverse edges of this top sheet along the corresponding outer parts of the cushion and connected at their lower ends with the transverse flanges of the base; a rear flap 62 extending downwardly from the rear edge of the top sheet 60 along the rear part of the cushion and connected at its lower edge with the rear part of the base; 25 and a front flap 63 extending downwardly from the edge of the top sheet 60 along the front side of the resilient means and connected at its lower edge with the front side of the front furniture bar 20 by means of tacks 64, as shown in Fig. 2, 30 or by any other suitable means.

The connection between the transverse walls and the rear wall of the base and the lower edges of the transverse end flaps and the rear longitudinal flap of the covering is preferably effected 35 by utilizing the channel-shaped flanges on the corresponding parts of the base for this purpose. This is accomplished by folding the lower edge portions of the rear flap and end flaps of the covering around the lower edges of the corresponding hook-shaped flanges of the respective walls of the base, as shown at 19 in Figs. 2, 3, 4 and 7, then doubling the lower edge portions of each of these flaps so that they engage with the concave or inner side or channel of these flanges, 45 as shown at 18 in the same figures, and then clamping these doubled portions of the covering flaps in these channels by means of clamping members having preferably the form of bars or strips 65, which latter are pushed upwardly 50 into the inner sides of the doubled portions of these flaps and press the same tightly against the concave inner sides of these flanges, as shown in these figures.

These clamping strips are so proportioned that 55 the same produce a wedge action upon those portions of the covering flaps which are arranged within the channels of the wall flanges and exert a grip against the same which will hold these flaps frictionally within these channels and prevent disconnection of these parts while in use. When this spring cushion device is assembled with the furniture frame the underside of the several clamping strips 65 engage with the shoulders or shelves 23 which are formed on the furniture 60 frame bars or rails for the reception of this cushion, thereby confining these clamping strips within the channel-shaped flanges of the base walls and insuring a firm connection of the covering flaps with the respective parts of the base.

For the purpose of preventing the retaining strips or bars 65 from becoming detached from the channels of the base when the latter is not resting with the channeled flanges of its walls on the furniture frame, locking means are provided 70

which are preferably formed integrally with the walls of the base. In the preferred form of these locking means shown in Figs. 2-6 a locking lip 47 is stamped or cut out of the sheet material of the vertical side wall and then bent outwardly and upwardly so that the inner end of the lip remains attached to the wall and the outer part bears against the underside of the retaining strip 65 and the doubled edge portion of the covering secured in the respective channel.

In order to permit this lip to be bent outwardly easily and conveniently by means of any suitable tool after the retaining strip has been inserted the area of the base wall immediately adjacent to the lower end and side edges of the slit in the wall forming the lip is deflected or dished inwardly so as to form a recess or pocket 48 in the wall into which the lip 47 projects downwardly and exposes its lower end and side edges before being bent, as shown in Figs. 5 and 6, and therefore permits a tool, such as a screw driver or the like to be inserted behind the lip preparatory to bending the latter outwardly and upwardly against the underside of the retaining strip and double part of the covering, as shown in Figs. 3 and 4.

Other means may be provided for preventing a separation of the clamping strips from the base flanges, such as the punch marks or spurs 66 which are preferably struck out of the stock of the base walls in line with the channels of the hook shaped flanges, and engaging these spurs or indentations with the inner sides of the clamping bar or strip 65, as shown in Fig. 7, thereby positively preventing separation of these clamping strips under all circumstances, particularly when transporting the spring cushions from one place to another while assembling the same with the furniture frames.

In order to avoid metallic engagement of the lower convolutions of the springs silencing means are provided which in their preferred form consist of strips 67 of burlap or similar woven or flexible material placed upon the bottom of the base and between the lowermost convolutions of the

springs and the next upper convolutions of the same, as shown in Figs. 1, 2 and 3.

This spring cushion is comparatively simple in construction, it has no parts which are liable to get out of order, thereby insuring maintenance of the same in a satisfactory and operative condition, and the same is also capable of being manufactured at low cost.

We claim as our invention:—

1. A cushion for furniture comprising a wall 10 provided at its upper edge with a downwardly turned flange arranged on the exterior of said wall and forming a downwardly opening channel, a flexible covering having a marginal part which is reversely folded twice in succession, a 15 clamping member arranged in said channel and adapted to hold the first reversely folded part of said covering around the lower edge of said flange and the second reversely folded part of said covering within said channel, and a supporting bar 20 provided with a rabbet which receives said channeled and folded parts.

2. A cushion for furniture comprising a wall provided at its upper edge with a downwardly turned flange arranged on the exterior of said 25 wall and forming a downwardly opening channel, a flexible covering having a marginal part extending into said channel, a clamping member arranged within said channel and engaging with the marginal part of said covering therein, and 30 means for retaining said clamping member in said channel and in engagement with said marginal part of the covering consisting of a lip struck out of said wall and bent outwardly and upwardly against the underside of said clamping member, and that part of said wall adjacent to the free end and sides of said lip being deflected inwardly and forming a recess whereby access is obtained from the outer side of said wall 35 to said lip for bending the latter from the wall 40 against said clamping member.
